ARROWHEAD STRUCTURE

Burton D. Smith, Duarte, Calif.
(7125 SW. Highway 217, Beaverton, Oreg.)
Filed July 6, 1959, Ser. No. 825,324
1 Claim. (Cl. 273—106.5)

The present invention relates to arrowhead structure and has particular reference to arrowhead blades, and ferrules for detachably mounting the blades on the forward end of an arrow shaft.

The conventional hunting arrow used for large game has a broadhead permanently affixed on the forward end of the shaft. The broadhead is kept razor sharp so that if the arrow misses a vital spot it will nevertheless kill effectively by severing arteries and vessels, causing the animal rapidly to bleed to death. Otherwise, with a dull blade, arteries and vessels tend to ride up and over it during passage and, unless a vital spot is hit, the animal will escape only to suffer unnecessarily.

The razor sharp arrowhead permanently connected on the end of the arrow shaft poses certain problems. Among these first may be mentioned that such arrows are extremely dangerous objects and must be treated as such at all times. Secondly, the hunter who conveniently carries only a few arrows is burdened with the problem of sharpening arrowheads in the field as they become dulled and nicked; and, the frequent sharpening of arrowheads eventually causes them to lose sufficient weight to upset the balance of the arrow. Moreover, the likelihood of dulling, nicking or breaking the arrowhead discourages the otherwise desirable use of hunting arrows for practice warm-up shots in the field. Replacing a worn or broken arrowhead is a tedious operation because of the strong permanent-type connection required between the arrow shaft and the arrowhead.

In accordance with the present invention there is provided an arrowhead structure including a ferrule adapted to be fixed on the forward end of an arrow shaft, and a cooperating substantially flat blade detachably insertable onto said ferrule. The ferrule has a body, a leading locating lug centered across the front end of the body, and a pair of substantially coextensive spaced flanges which extend laterally from each of opposite sides of the body approximately in a common plane with the leading lug, with each pair of flanges defining therebetween an open longitudinal channel. The rear outline of the cooperating blade has a deep central recess, the crotch of which matches the front configuration of the leading locating lug of the ferrule and portions of the surrounding margin of which fit within the longitudinal channels of the ferrule. Further, means are provided for releasably locking the blade on the ferrule.

A ferrule constructed in accordance with the preferred embodiment of the invention includes a pair of trailing locating lugs respectively disposed on opposite sides of the body in the channels formed between the flanges. The ferrule is made from two mating half sections having body portions which cooperate to define a socket for the front end of an arrow shaft. The half sections have forward positions in the form of substantially flat tabs held together to form the leading lug, and laterally extending side portions or flanges held together in spaced relationship by cross members which form the trailing lugs. Further, a detachable arrowhead blade constructed in accordance with the preferred embodiment of the present invention comprises a substantially flat body having a forward outline and a rear outline, with the rear outline of the body having a deep central recess and two relatively shallow recesses disposed respectively on opposite sides of the central recess, whereby

2

the body has a major and two minor bifurcations looking rearwardly thereof.

Thus in accordance with the present invention, the main blade itself, not a mere appendage thereto, is detachable. The structure is simple, and the combined ferrule and blade neither add nor detract materially from the normal size, weight and shape of the conventional arrowhead. Combined with the foregoing characteristics is the important fact that the ferrule provides a firm and stable support for the blade so that the composite structure is comparable in strength and stability to the conventional one-piece arrowhead. The importance of this becomes obvious when one considers the force and impact to which the arrowhead is subject, and related facts such as the fact that distortion of the arrowhead affects the flight of the arrow.

The problems pointed out with respect to the conventional arrowhead as related to the requirement that it should have a razor-sharp edge are substantially resolved by the arrowhead of the present invention. Thus employing the arrowhead structure of the present invention, one can easily remove the sharp blade from the arrows so that they are not dangerous to keep or transport. The hunter in the field can easily carry extra blades and insert new blades as needed, leaving his sharpening problems at home. There is less deterrent to the use of hunting arrows for practice warm-up shots, and the replacement problem arising from blade breakage or from the eventual loss in weight due to sharpening is less consequential, both in terms of time and money.

The preferred embodiment of the arrowhead structure of the present invention is described in greater detail with reference to the accompanying drawings, in which:

FIG. 1 is a plan view of a detachable arrowhead blade constructed in accordance with the present invention;

FIG. 2 is a plan view partially cut away showing the blade of FIG. 1 inserted onto and locked to a ferrule constructed in accordance with the present invention, the ferrule being in turn affixed to the forward end of an arrow shaft;

FIG. 3 is a side elevational of the apparatus of FIG. 2;

FIG. 4 is a sectional view taken along line 4—4 of FIG. 2;

FIG. 5 is a side elevation of the ferrule of FIGS. 2 and 3 with the blade and shaft removed; and,

FIG. 6 is a fragmentary view taken along line 6—6 of FIG. 4;

Referring now to the drawings, there is shown a detachable arrowhead blade 10, and a cooperating ferrule 12 for mounting the blade on the forward end of an arrow shaft 14. The blade and ferrule are made of steel and, together assembled, have the form of a broadhead, as shown.

The ferrule 12 comprises two mating half sections 16, 18 having body portions 20, 22 respectively which together constitute the body of the ferrule and which cooperate to define a socket 24 for the front end of the arrow shaft 14. The ferrule is permanently connected on the front end of the arrow shaft with conventional heat setting cement.

The mating half sections 16, 18 have forward portions in the form of substantially flat tabs 26, 28 respectively. The tabs are held together by a rivet 30. Together, they form a leading locating lug 32 which extends centrally across the front end of the body.

The first half section 16 has laterally extending opposite side portions or flanges 34 and 36. These flanges are paired with similar flanges 38, 40 respectively of the second half section 18. The result is a first pair of spaced and substantially coextensive flanges 34, 38 which define therebetween an open longitudinal channel 42, and a second and similar pair of spaced and substantially co-

extensive flanges 36, 40 which define therebetween a second and similar open longitudinal channel 44. The two pairs of flanges extend from opposite sides of the body of the ferrule, approximately in a common plane with the leading locating lug.

The flanges 34, 38 of the first pair are securely held in spaced relationship by a first cross member 46 disposed outwardly from the body of the ferrule and consisting of an annular spacer 48 secured in the channel 42 between the flanges by a rivet 50. The annular spacer 48 acts as a first trailing locating lug.

Similarly, the flanges 36, 40 of the second pair are securely held in spaced relationship by a cross member 52 disposed outwardly from the body of the ferrule and consisting of an annular spacer 54 secured in the channel 44 between the flanges by a rivet 56. The annular spacer 54 acts as a second trailing locating lug, correspondingly disposed on the opposite side of the body of the ferrule with respect to the first trailing locating lug.

The cooperating blade 10 is a flat piece of steel having a razor sharp leading edge 58. Its front outline, as defined by this edge, is that of the conventional broadhead. It may, of course, have a different front outline than that illustrated. The trailing edge or rear outline of the blade is blunt and has formed therein a relatively deep central recess 60, and two relatively shallow recesses 62, 64 disposed respectively on opposite sides of the central recess, whereby the blade has one major and two minor bifurcations looking rearwardly thereof. A notch 66 is formed on the inner edge of a portion 67 of the blade lying between the central recess 60 and side recess 62; and, a corresponding notch 68 is formed on the inner edge of a portion 69 of the blade lying between the central recess 60 and the other side recess 64.

As can be seen from FIGS. 1 and 2, the crotches of the central and side recesses of the blade are semicircular and the recesses are open and unobstructed along the rearward longitudinal projection of their crotches. The front surfaces of the leading and trailing locating lugs are also semicircular, and match the crotches of the central and side recesses respectively both in configuration and in relative location.

The blade 10 may be inserted onto the ferrule 12 to a position where the leading locating lug abuts the crotch of the central recess 60 with portions 70, 72 of the margin of the central and side recesses fitting within the longitudinal channels 42, 44 and with the crotch of each side recess abutting respectively the corresponding trailing locating lug. The mounted blade is disposed approximately in a common plane with the flanges and locating lugs so that the combined configuration is that of the conventional arrowhead, while at the same time, an extremely stable and solid support is provided for the blade on the ferrule.

The blade 10 may be releasably locked in position on ferrule 12 by means of an open ended snap ring 74 which engages the portions 67, 69 of the blade between the central and side recesses. The first half section 16 of the ferrule has formed in its body portion 20 a laterally extending slot opening 76 which extends between open-

ings 78, 80 drilled respectively through each pair of flanges at a location adjacent the body of the ferrule. When the blade 10 is inserted into the ferrule so that the crotches of the recesses abut the locating lugs, the notches 56, 68 register with the openings 78, 80 so that the snap ring 74 may be inserted. The snap ring is itself notched at opposite ends and conventionally, like a small spring, may be pressed into place whereby its notched ends snap outwardly over the slanted edges of the notches 66, 68 in the blade, as shown in FIGS. 4 and 6. The interposition of the snap ring in the openings 78, 80 and within the notches 66, 68 locks the blade to the ferrule, and the notched ends of the snap ring itself secure the snap ring in position by locking over the blade.

As can be seen in FIG. 2, the arrow shaft is indented slightly at 82 to accommodate the snap ring so that, as best seen in FIG. 3, the snap ring does not protrude from the body of the ferrule, but lies substantially even with the surface of the ferrule.

I claim:

An arrowhead construction comprising a ferrule adapted to be fixed on the forward end of an arrow shaft, the ferrule having a body, a solid leading locating lug centered across the front end of the body, a pair of substantially coextensive spaced flanges extending laterally from each of opposite sides of the body and approximately in a common plane with the leading lug, each pair of flanges defining therebetween an open longitudinal channel, and also having a pair of trailing locating lugs respectively interconnecting said spaced flanges of each pair on opposite sides of the body and extending across said channels, said ferrule having an opening through each pair of flanges and an open slot which extends laterally around its body between said openings in the flanges, a cooperating substantially flat blade detachably insertable on said ferrule, the rear outline of the blade having a deep central recess and a relatively shallow recess on each side of the central recess, with the crotches of the central and side recesses matching the front configuration of the leading and trailing locating lugs respectively for abutting the same and with portions of the blade located between the central and side recesses fitting within said longitudinal channels, said portions of the blade located between the central and side recesses having notches therein which register with the openings through the flanges, and locking means engageable with said portions of the blade located between the central and side recesses for releasably locking the blade on the ferrule, the locking means comprising an open ended snap ring which fits into said slot with its opposite ends extending through said openings in the flanges and registering notches in the blade.
